UNITED STATES PATENT OFFICE

STEPHEN J. TRACY, OF PALISADES PARK, NEW JERSEY.

LIFE-SAVING APPARATUS FOR SHIPS.

1,120,866.

Specification of Letters Patent. Patented Dec. 15, 1914.

Application filed May 2, 1914. Serial No. 835,840.

To all whom it may concern:

Be it known that I, STEPHEN J. TRACY, a citizen of the United States of America, and residing at Palisades Park, in the county of Bergen and State of New Jersey, have invented new and useful Improvements in Life-Saving Apparatus for Ships, of which the following is a specification.

The object of my invention is to provide in simple and quickly accessible form a practical means of communication between ships at sea for life saving purposes.

A special object is to provide an inexpensive and compact equipment of this character which may be readily applied to all vessels and which will render such vessels capable of either rescuing passengers from other vessels, or of sending off their own passengers, as necessity may require.

To these ends, one feature of the invention consists of a transporting cable which is stretched between the communicating vessels and is automatically maintained in the tautened condition necessary for transportation between the vessels irrespective of the relative movement and the distance between the vessels. This automatic tensioning of the cable is obtained by connecting the cable at one end to one vessel and at the other vessel passing it over an outboard support and weighting the outboard portion of the cable sufficiently to counterbalance the weight of the span of cable and the load carried thereby. The load will usually be carried in a car traveling on the cable and suitable for passenger or cargo carrying purposes, as the case may be.

For the sake of providing landing stages on the vessels at the ends of the span of cable, the cable is preferably made fast to the first vessel at a point inboard and above the deck and at the second vessel the cable is passed over an elevated inboard support before it passes over the outboard support which carries it over the side of the vessel. Usually the outboard or weighted end portion of the cable is formed into a loop and the weight is supported in the bight of this loop so that by taking up or paying out the cable at the standing end of the loop the weight may be raised or lowered in accordance with the depth of sea and without affecting or being effected by the carrying span of the cable. A lead line may be attached to the weight to form an indicator whereby the weight may be kept at a safe

depth at all times, and a similar line may be stretched between the ships so that with the length of span known, the counterweight necessary to keep it properly taut may be known with certainty and so be employed.

Another feature of the invention consists of a life net which is supported off from the side of the rescuing ship and extends down into the sea on an outward incline so that the effect of the waves will be to wash person up the incline of the net to a position of safety. The value of this net is further enhanced by the employment of a hand line or lines extending from the rescued ship into the midst of the net whereby persons on such line or lines will be carried with certainty into the net. Usually the net will be divided in two parts so as to lie on opposite sides of the stem of the ship and will extend from the deck line well down into the water.

Other features of the invention will appear as the specification proceeds.

The accompanying drawings illustrate a practical embodiment of the invention but as this is for illustrative purposes, it will be understood that various changes and modifications may be made without departing from the true scope and spirit of the invention.

Figure 1, is a more or less diagrammatic representation of the invention as in use in the rescue of persons from a disabled ship at sea. Fig. 2, illustrates the rescue of persons from a ship stranded on a bar. Figs. 3 and 4 are enlarged side and top plan views of the portion of the apparatus usually carried by the rescue ship. Figs. 5 and 6 are similar views of the apparatus carried by the disabled ship. Fig. 7, is a detail view illustrating a form of swivel mounting for the pulley block which supports one end of the cable. Fig. 8, is a perspective view of a passenger carrying car for transporting passengers from one vessel to another.

In the first six figures, A represents a vessel in distress and R a rescue ship. 7 is the so-called "transporting" cable forming the connecting link for the transport of passengers from the rescued to the rescuing vessel. 8 designates a car traveling on said cable and drawn therealong by suitable means, such as the line 9. The transporting cable is maintained in the tautened condition necessary for transporting purposes by means of a weight 11 applied to the end of

the cable. This weight and the length of cable which directly supports it is kept from fouling with the ship by passing the cable over an outboard support such as the sheave 12 supported in brackets 13 outstanding from the side of the ship. In the preferred practice this outboard cable support will be located at the stern of the vessel where it is inconspicuous and out of the way. Ordinarily in operation the weight will be suspended from the stern of the disabled vessel and at the other end the cable will simply be made fast at some convenient point on the rescue vessel.

To provide landing stages at the ends of the span of cable, the cable is preferably brought inboard and elevated above the deck. At the weighted end this is accomplished by passing the cable over an elevated inboard support such as the sheave 15 on the mizzenmast 14 before it goes down over the outboard support into the sea and on the other ship the cable may be connected to the mast or to a temporary support such as indicated at 16, placed inboard and elevated above the deck. The sheave 15 is usually swiveled as indicated at 17 in Fig. 7 to allow for lateral movements of the vessels. Usually the embarking end of the cable will be higher than the other end so as to facilitate the passage from one ship to the other and at this higher end, where the cable is usually supported at an elevated point on the mast, a platform 18 may be provided. At the lower or receiving end the cable may be supported at the right height for the passengers to be landed on the deck or a landing platform may be provided if desired.

To permit of the raising and lowering of the weight to suit different depths and for the purpose of adding to or subtracting more or less weight in accordance with the length of span and weight of load, without slackening off the span, the weight is preferably supported in a loop of cable which may be lengthened or shortened at will. This loop is designated 20 and the weight is shown provided with a sheave 21 riding in the bight of the loop. The standing end of this looped portion of cable passes up over a roller 22 and may be made fast to a capstan or windlass 23. By raising or lowering on the standing end of the loop it will be obvious that the weight may be lifted or lowered without affecting or being affected by the span of cable.

The passenger carrying car may be of any suitable construction and is here shown as consisting of a wooden slat bottom 25, suspended by two arched hangers 26 from supporting wheels or trolleys 27 riding on the cable and having network sides 28, connected at the ends by gates in the form of hooked bars 29.

65 The transporting cable is passed from one

vessel to the other in any suitable way, as by first shooting a messenger line from one ship to the other or by picking up a buoyed line dropped from one vessel to the other, and then drawing the cable across with the aid of this line. The ships are usually maneuvered so that the rescuing vessel will lie to leeward of the disabled ship so that the transfer from one vessel to the other will be assisted by the elements. In order that the automatic tensioning of the cable shall not interfere with the transfer of passengers, the weighting of the cable is preferably at the disabled ship end of the cable and the cable is simply made fast in any convenient manner on the rescuing ship as by connecting it to a davit or to a capstan 30. When the cable has been made fast on the rescue ship, the weighted end of the cable is lowered into the sea. This may be done by carrying forward the proper length of overboard cable and attaching the weight thereto, as indicated in dotted lines at 32 in Fig. 5, and then when all is ready, releasing the weight and allowing the cable and attached weight to swing down into position off the stern. For the weight I prefer to use an anchor chain which as indicated, may be formed into loops 33, as many in number as may be necessary to properly counter-balance the span of cable and the load which it is to support. The length of span being known and the weight of a definite length of chain being known, the necessary amount of chain may be quickly ascertained and be employed. A distance line 34, between the ships with suitable markings in the nature of a lead line, may be used so that the length of span will be known at all times. The weight will preferably be sufficient to allow for variations of a hundred feet or so in the length of the span. Upon an undue increase or decrease in the length of the span, the weight may be drawn up by taking in the loop 20 of cable, and weight necessary to compensate for the changed conditions, be added or subtracted, as the case may be, and it will be noted that this compensation is accomplished without affecting the carrying span of the cable. A lead line 35 may be connected with the weight so as to indicate at all times the depth of the weight in the sea. This indication also gives notice of the fact that the vessels may be drawing nearer together or farther apart.

In conjunction with the cableway, I may employ a net, such as indicated at 40. This net is shown divided into two triangular sections 41 and 42, shaped to lie on opposite sides of the stem of the rescue ship. The net is supported by a transverse beam 43 at the top, disposed athwartship and two spars 44 outstanding from the sides of the ship. The base ends of the spars are swiveled in suitable sockets 45 and the forward ends are

secured in the outer corners of the nets at 46 so as to hold the net sections distended. Lines 47 serve to draw the spars outward so as to stretch the net properly and lines 48 dependent from the ends of the athwartship beam support the outward ends of the spars and regulate the depth of the net in the sea. The edges of the net may be caught up as indicated at 49 to form side walls. The downward and forward inclination of the net assists very materially in the rescue work because the natural effect of the waves is to wash persons in the sea up the incline of the net and the incline is such as to practically support without effort anyone resting on the net. The net will usually extend up over the deck rail so that the passage may be made unassisted from the water up onto the deck.

20 Hand lines 50 may be run from the disabled ship to the rescue ship and when the life net is employed, these lines will preferably be run into the net so that persons in the sea will be guided and positively directed into the net. Usually these lines will be passed through the net, over guides 51 in rear of the net and have attached thereto the weights 52 for keeping a suitable tension on the lines.

30 When the life net is to be used the athwartship supporting beam 43 will be secured in position, the net will be secured to the ends of the spars and then when the spars have been engaged in their sockets, 35 they will be lowered and the side lines 47 will be tightened to hold the net distended. The net may be steadied and held down at the center by a stem boom 56 forked at its lower end 57 to engage opposite sides of the 40 stem and pivotally supported as at 58 so that it may be lowered with the net.

The net and the hand lines being disposed substantially in the path of travel of the passenger conveyance on the cable assist in saving any persons who might fall from the conveyance into the sea.

In case of a high sea, oil bags 54, or equivalent means may be employed for reducing the effect of the waves. These bags 55 will as shown be thrown over from the vessel to windward so as to calm the sea about the vessel to leeward.

Fig. 2 indicates the use of the invention in rescuing lives from a vessel driven ashore on a bar or reef, which due to stormy conditions cannot be reached by boats from the beach. In this case, after the transporting cable has been carried to the wrecked ship and there made fast, the weight necessary to 60 balance the load and the span of cable between the wreck and the relief ship, is attached to the cable and lowered overboard. The passengers are then transferred to safety on the relief ship by way of the car traveling on the cable. Preferably this car

is large enough to carry a number of persons in one load. The hooked bars closing the ends of the car permit of the quick loading and unloading of the car.

For the sake of lightening the load on the 70 cable as much as possible the hauling line 9 is usually operated from a higher level than the cable so that the pulling will also exert a lifting tendency on the car. This feature is shown in Figs. 3 and 5 where the hauling 75 line 9 is passed over blocks 59 placed at higher elevations than the transporting cable. A convenient means of attaching this line to the car is to connect it with an eye 80 carried by a brace bar 61 connected between the two arches of the car.

When lowering the weight into the sea, the cable is usually held at the end where the weight is being lowered so as to prevent too sudden a strain being applied to the 85 stretch of cable between the ships. In the present instance, this is accomplished by applying a clamp 63 to the cable at a point near the support 15, which clamp, as the weight is lowered, engages with said support, thereby relieving the stretch of cable 90 of all strain. When the weight has been lowered, the distance between the vessels may be increased enough to bring the stretch of cable taut, whereupon the load will then 95 be taken off the clamp, which may be removed so as not to interfere with the automatic tensioning action.

If at any time it becomes necessary to materially increase the counterbalancing 100 weight—as in a case where it is found necessary to carry more passengers at a trip, this may be done by applying a clamp 65 on the standing end side of the weight loop 20. When this clamp is allowed to come 105 in engagement with the weight sheave 21, as by lowering on the standing end of the loop, the entire weight is then transferred to the working end of the loop and hence becomes a dead weight sustained entirely 110 on the end of the transporting cable. By putting this clamp on the working end of the weight loop it will be seen that the weight may be taken off the transporting cable and be transferred wholly to the standing 115 end of cable.

Very material assistance in keeping the vessels properly spaced apart is provided by making the lead line 34 fast to one vessel and at the other end connecting it with an 120 instrument 70 located in the pilot house or other convenient point, which will give the information necessary for the maintenance of the proper separation between the ships. In the illustration this instrument has a 125 drum 71, around which a turn of the line 34 is taken after the ships have been maneuvered into the proper relation. The end of the line may be guided over the ship's side and be provided with a weight 72. As the 130

ships separate, the drum of the indicator will rotate in one direction and as they approach, the drum will rotate in a reverse direction. The indicator being provided with suitable reference characters or dials, the one in charge of the ship is thus kept informed of the relative movements of the ships and can govern his ship accordingly. The distance line will usually be made of piano wire which is relatively light and possesses the necessary strength and flexibility. In addition to the equipment described each vessel will preferably carry an outboard support at the stem as well as at the stern so that in the case of a ship sinking by the stern, the weight may be lowered over the bow. An outboard stem support of this character is indicated at 74 in Figs. 1 and 3. With this additional equipment the counterbalancing weight may be supported from whichever end of the vessel is the most handy and free from danger.

It is evident that my invention is of such simple character that it may be readily carried by all vessels without adding sensibly to the cost thereof and that while inconspicuous and out of the way when not in use, it may be quickly erected and put into use. In particular the invention forms a valuable addition to the equipment ordinarily carried by revenue cutters and the like vessels engaged in patrol and rescue service.

What I claim is:—

- 35 1. Life saving apparatus for ships, comprising a cable fast at one end to one ship and extending from said ship to another ship, an inboard support on said latter ship over which the cable is passed to provide a 40 cableway from the first ship to a landing stage on the second ship, an outward support over which the cable from the inboard support is passed down over the side of the ship and a weight carried by the said downwardly extending outboard portion of the cable and sufficient in extent to counterbalance the stretch of cable between the ships and the load sustained by said stretch of cable.
- 45 2. Apparatus of the character described, comprising, a span of cable between two ships, an outboard support on one of said ships over which the end portion of said cable is passed overboard down into the sea, a weight on the said overboard dependent end portion of cable sufficient to counterbalance the weight of the span of cable and the load to be sustained thereby and a conveyance traveling on the span of cable.
- 50 3. Life saving apparatus for ships, comprising a cable fast at one end to one ship and extending from said ship to another ship, an elevated support on said latter ship and over which the cable is passed to

thereby provide a cableway between the ships, a landing platform beneath the said elevated support, an outboard support over which the cable from the inboard support is passed down over the side of the ship into the sea, a conveyance traveling on the stretch of cable between the ships and a weight carried by the overboard portion of the cable substantially equal in value to the combined weight of the loaded conveyance and the stretch of cable between the ships.

4. A life saving apparatus for ships, comprising a cable extending from one vessel to another and formed at one of the vessels into a dependent loop supported outboard over the side of said vessel, whereby the standing end of said loop may be lowered or drawn up at said vessel to increase or decrease the amount of the loop extending down into the sea, a sheave riding in the bight of said loop and a weight supported by said sheave and substantially equal in value to the weight of the length of cable between the vessels and the load to be supported by said length of cable.

5. As a means of communication between vessels at sea, a supporting cable fast at one end to one vessel and extending from said vessel to another vessel and formed at said latter vessel into a dependent loop supported outboard over the side of said vessel, a weight supported in the said overboard dependent loop of cable and means for taking up and paying out the standing end of said dependent loop of cable whereby to raise and lower the weight without affecting the span of cable between the vessels.

6. A life saving apparatus for ships, comprising a cable fast at one end to one ship and extending from said ship to another ship, an inboard support on said latter ship over which the cable is passed to provide a cableway from the first ship to a landing stage on the second ship, an outboard support over which the cable from the inboard support is passed down over the side of the ship, a weight carried by the said downwardly extending outboard portion of the cable and sufficient in extent to counterbalance the stretch of cable between the ships and the load sustained by said stretch of cable and a stop adjustably clamped on the cable adjacent the inboard support.

7. Life saving apparatus for ships, comprising a cable extending from one vessel to another and formed at one of the vessels into a dependent loop supported outboard over the side of said vessel, whereby the standing end of said loop may be lowered or drawn up at said vessel to increase or decrease the amount of the loop extending down into the sea, a weight supported in the bight of said loop and substantially equal in value to the weight of the length of cable between the vessels and the load to be sup-

ported by said length of cable and a stop adjustably clamped on one of the sides of the said loop of cable.

8. Life saving apparatus for ships, comprising a net, means supporting said net off from the side of a ship and dependent into the sea, a support on the ship in rear of the net, a hand line extending from another ship through the net and over the support in rear of the same and a weight on the hand line below the support for maintaining the stretch of line between the two ships relatively taut.

9. Life saving apparatus for ships at sea, comprising a net, means supporting said net outstanding from the side of the rescuing ship and dependent into the sea on an incline whereby the effect of the waves will be to wash persons up the incline of the net and a hand line extending from the rescued ship into the inclined net of the rescuing ship.

10. Life saving apparatus for ships at sea, comprising a net divided to lie on opposite sides of the stem of a ship and extending from above the water line down into the sea, and means for supporting the divided portions of the net outstanding from the sides of the ship and inclined downwardly and forwardly into the sea.

11. Life saving apparatus, comprising in

combination, a transporting cable connected between a rescuing ship and a ship in distress, a passenger conveyance traveling on said cable, means for applying tension to said cable and a life net carried by the rescuing ship and dependent on an incline into the sea substantially in line with the path of travel of said conveyance over the cable.

12. Life saving apparatus, comprising a supporting beam extending athwartship the bow portion of a ship, spars supported from said beam and extending from the sides of the ship down into the sea, a net secured to the lower ends of said spars and held distended thereby and a dependent boom carried by the stem and engaging the intermediate portion of the net between the spars.

13. In apparatus of the character described, a load-carrying cable connected between two relatively movable vessels, a distance line connected between the vessels, and a distance indicating instrument on one of said vessels operated by said distance line to thereby indicate at all times variations in the length of load-carrying cable between the vessels.
